US0D1059548S

(12) **United States Design Patent** (10) **Patent No.:** **US D1,059,548 S**
(45) **Date of Patent:** **** Jan. 28, 2025**

(54) **FOGGER**

(71) Applicant: **Zhejiang Prulde Electric Appliance Co., Ltd.**, Jinhua (CN)

(72) Inventor: **Weiming Yang**, Jinhua (CN)

(73) Assignee: **ZHEJIANG PRULDE ELECTRIC APPLIANCE CO., LTD.**, Jinhua (CN)

(**) Term: **15 Years**

(21) Appl. No.: **29/758,404**

(22) Filed: **Nov. 15, 2020**

(30) **Foreign Application Priority Data**

Aug. 26, 2020 (CN) 202030494824.5

(57) **CLAIM**

The ornamental design for a fogger as shown and described.

DESCRIPTION

FIG. 1 is a front elevation view of a fogger showing my new design.

FIG. 2 is a rear elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a perspective view thereof.

FIG. 8 is another perspective view thereof.

FIG. 9 is another perspective view thereof.

FIG. 10 is the perspective view of FIG. 8 with an indication of an area A enlarged in FIG. 11; and,

FIG. 11 is an enlarged view of the area A in the perspective view of FIG. 10.

The dot-dash broken lines indicating an enlarged portion in FIGS. 10 and 11 form no part of the claimed design.

1 Claim, 11 Drawing Sheets
